UNITED STATES PATENT OFFICE.

HERBERT L. GLAZE, OF LOS ANGELES, CALIFORNIA, ASSIGNOR, BY MESNE ASSIGNMENTS, TO PLASTOID PRODUCTS, INC., OF LOS ANGELES, CALIFORNIA, A CORPORATION OF CALIFORNIA.

ARTICLE OF MANUFACTURE.

1,356,707.

Specification of Letters Patent. Patented Oct. 26, 1920.

Application filed April 17, 1919. Serial No. 291,982.

To all whom it may concern:

Be it known that I, HERBERT L. GLAZE, a citizen of the United States, residing in the city of Los Angeles, county of Los Angeles, 5 and State of California, have invented a certain new and useful Article of Manufacture, of which the following is a specification.

My invention relates to plaster board and 10 the like, and has as its principal object to provide a small piece of plaster board, or other like article, made of brittle material and easily broken, which shall be free of corners or angles so easily broken when handled or 15 when the edge thereof is pinched with the fingers in a test of its strength. I have discovered that a small, round piece of composition board is most difficult to break on the edge. Therefore the real essence of my invention 20 is the form of the piece used for sample purposes, intended to be much handled and thrown around, and the form of the sample is, therefore, the principle of the invention. Of course I do not claim that the mere making 25 of an article round is invention separate and apart from the kind of article. This invention relates to plaster board and the like, made of brittle material, sometimes covered with sheet material, such as paper, 30 cloth and the like. If in square form or in a form having corners or angles, I have found from experience that these corners and angles are easily broken and little by little, always in the form of corners or

points, the sample is worn away and its appearance made rough and undesirable. 35

I have discovered that by making a sample of plaster board or the like with continuous rounded edges, and eliminating all corners or angles to be broken, the sample 40 can be used a long time and its edges will remain uniformly smooth and even, and in fact, it is difficult to break out a piece of said plaster board.

I have illustrated such a piece of plaster 45 board on the accompanying sheet of drawings, in which Figure 1 is a perspective view of a sample of plaster board, showing the top cover sheet partially turned back; and, Fig. 2 is a straight flat view thereof. 50

In the drawings, the body of the plaster board is designated 1, and the covering of sheet material is designated 2.

What I claim to be new, therefore, and desire to protect by Letters Patent is, 55

In plaster board and like material of brittle composition, a sample piece made with a continuous curved edge for the purpose of preventing breakage of the edge thereof in handling and testing in the hands, 60 substantially as described.

Signed at Los Angeles, Los Angeles county, California, this 28 day of February, 1919.

HERBERT L. GLAZE.

In presence of—

W. R. LITZENBERG,
H. M. BRUNDAGE.
